COUPLER SUPPORT

Frank H. Kayler, Alliance, Ohio, assignor to
American Steel Foundries, Chicago, Ill., a corporation of New Jersey

Application January 9, 1952, Serial No. 265,606

12 Claims. (CL. 213—61)

1

This invention relates to a novel support for the shank of a railway car coupler and more particularly to a support of the type wherein a carrier iron is resiliently mounted on a striking casting and is adapted to afford support for the coupler shank. The present application is a continuation-in-part of my copending application Serial No. 605,233, filed July 16, 1945, now Patent Number 2,604,215.

A primary object of the invention is to provide a novel arrangement wherein the striking casting affords resilient support for a carrier iron which in turn resiliently supports the coupler shank at a desired height during normal operation and permits the shank to move horizontally and vertically for adjustment to various truck conditions.

A more specific object of the invention is to maintain the supporting springs for the carrier iron under precompression by means which can be readily assembled and disassembled from the sides of the car body.

Another object of the invention is to devise a coupler support such as above described having provision for readily adjusting the height of the coupler shank to any desired coupling position.

Still another object of the invention is to facilitate assembly and disassembly of the carrier iron with respect to the striking casting by providing slots in the side walls thereof and by providing attachment means on the remote sides of the striking casting for removably anchoring the outer ends of retainer plates which project through the slots and are received at their inner ends within complementary recesses of the carrier iron to limit upward movement thereof and to thereby maintain the coupler supporting springs under precompression between the carrier iron and the striking casting.

A further object of the invention is to reduce stresses on the anchoring means for the retainer plates by providing outturned flanges on the striking casting above its slots, said flanges affording bearing for the retainer plates along a major portion of their length, whereby the carrier iron upon engagement with the plates acts through relatively short lever arms thereof to stress the anchoring means.

Yet another object of the invention is to form and arrange the striking casting and carrier iron to accommodate maximum spring capacity within the available space and to afford positive positioning of the springs.

The foregoing and other objects and advantages of the invention will become apparent from a consideration of the specification and the accompanying drawings, wherein:

Figure 1 is a front view of a coupler support embodying a preferred form of the invention, with portions of the structure in section on the line 1—1 of Figure 2.

2

Figure 2 is a sectional view on the line 2—2 of Figure 1.

Figure 3 is a top plan view of the coupler support with portions broken away to clarify the illustration, and

Figures 4, 5 and 6 are respectively a top plan view, a front elevational view, and a side elevational view of the carrier iron utilized in the arrangement of Figures 1 to 3.

Describing the invention in detail, the novel coupler support comprises a striking casting, generally designated 42, and adapted for support from the center and end sills (not shown) of a car body as described in detail in said copending application. The striking casting is preferably formed with a hollow, top, coupler-striking or stop portion 44 as well as depending carrier supports 46, and a carrier spring support, generally designated 48. The striking portion 44 is rectangular in form and is provided with an upstanding transverse flange 50 having openings 52 for riveting to a car body end sill (not shown) as described in said copending application.

The flange 50 is reinforced by longitudinal webs 54 (Figures 1 and 3) merging with said flange 50 and with a top wall 56 of the portion 44. A longitudinal web 57 extending parallel with the webs 54 also merges with the flange 50, the top wall 56, a striker wall 58 and a horizontal wall 60 spaced below the wall 56, as best seen in Figure 2. The web 57 also extends rearwardly to merge with a transverse wall 62 adapted for riveting to a car body end sill, as more fully described in the copending application.

Extending downwardly at opposite sides of the striking portion 44 are the above mentioned carrier supports 46 comprising substantially vertical side walls 64 merging at their lower extremities with a bottom wall 66 and with transverse front and rear walls 68 defining the before mentioned carrier spring support 48 having a pocket 70 between the walls 68 for convenient reception of carrier springs 72 which support a carrier iron generally designated 74.

Referring now to Figures 4 to 6 inclusive, the carrier iron 74 is of rectangular cup-like form for reception in the complementary shaped pocket 70 of the spring support 48. The carrier iron comprises a top wall 76 which is preferably formed of wear resistant material to support a coupler shank, generally designated at 77 in Figure 1, said shank having pivotal mounting for horizontal and vertical angling as fully described in the parent application.

The wall 76 is provided with a plurality of depending spring positioning bosses 80 received within the upper ends of the springs 72, the lower ends of which are similarly positioned by upstanding bosses 81 on the bottom wall 66 of the spring support 48.

3

The carrier iron wall 76 is also formed adjacent its edges with spaced transverse walls 82 and side walls 84, defining a pocket for reception of the springs 72, as best seen in Figures 1 and 2. The inner surfaces of these walls are arcuately formed as indicated at 88 in Figure 4 to afford convenient positioning for the lateral springs 72 at opposite sides of the center spring 72 and to afford maximum spring capacity consistent with adequate strength for service conditions.

Each carrier iron side wall 84 is formed with top and bottom outturned flanges 86, the top flanges merging with the underside of the top wall 76 and the bottom flanges being spaced from the top flanges 86 to define recesses receiving the inner ends of elongated retainer plates 88 riveted as at 90 to outturned flanges 92 integral with the related side walls 64 of the striking casting 42 and extending through slots 93 (Figure 1) in the related side walls 64 as best seen in Figures 1 and 3.

The retainer plates, as best seen in Figure 1, are anchored at their outer extremities by the rivets 90 or other convenient detachable securing means such as bolt and nut assemblies; and the inner ends of the plates 88 are engageable with the carrier iron lugs 86 to limit vertical movement of the carrier iron. In this connection it will be noted that normally the springs 72 are precompressed to maintain the coupler shank 77 at the height shown in Figure 1; however, downward movement of the shank 77 under service conditions results in further compression of the springs 72 which upon upward movement of the shank 77 urge the bottom stop lugs 86 of the carrier iron against the underside of the retainer plates 88 at their inner ends.

Inasmuch as the retainer plates 88 are subjected to repeated impacts by the bottom carrier iron lugs 86 under service conditions, the novel arrangement, best seen in Figure 1, affords bearing for the plates 88 for a major portion of their length against the underside of the flanges 92, so that the lugs 86 upon contact with the plates 88 under the action of the springs 72 act against the plates 88 through relatively short lever arms thereof, an arrangement which greatly reduces stresses on the rivets 90. It will be further noted that, although the slots 93 are illustrated in the drawings as bounded at their upper edges by outturned flanges 92 of the striking casting, if desired, the lower edges of the slots 93 may be similar bounded by outturned flanges through which the rivets or other suitable securing means may extend.

Furthermore, it will be understood that the thickness of the retainer plates 88 may be varied by the use of shims, or plates of other thicknesses may be substituted for the plates 88; and it will be understood that the precompression of the springs 72 is sufficient as above described to urge the stop lugs 86 of the carrier iron into engagement with the plates 88 when the coupler shank 77 is supported in its normal horizontal coupling position by the carrier iron. It will thus be apparent that the novel arrangement of plates 88 affords a simple method of adjusting the coupler shank 77 to its correct coupling height.

I claim:

1. In a coupler support, a member having means for attachment to an associated car body, said member having spaced substantially vertical parallel side walls, slots through said walls, pre-compressed spring means supported by said

4

member between said walls, a carrier iron supported by said spring means and having recesses registered with respective slots, retainer plates engaged at their inner ends with upwardly facing surfaces of said carrier iron, said plates being separable with respect to said member and bearing for a major portion of their length against downwardly facing surfaces thereof, and elongated members extending through openings of said downwardly facing surfaces and plates for retaining the latter in assembled relationship with the latter, said elongated members being spaced farther from the inner margins of the respective slots than the outer margins of the related upwardly facing surfaces, whereby reaction of said spring means against said plates is against relative short lever arms thereof to reduce consequent stresses on the elongated members.

2. A coupler support, according to claim 1, wherein the upwardly facing surfaces are formed on lugs projecting from the sides of the carrier iron, and wherein the carrier iron is formed with other lugs on the underside of the top wall of the carrier with their faces flush with the outer ends of the carrier top wall to give increased side guide bearing for the carrier against the side walls.

3. A coupler support, according to claim 1, wherein the downwardly facing surfaces are partly formed on outturned flanges of the side walls defining the upper edges of the slots, and the elongated members are provided with heads bearing against the upper surfaces of the flanges, said elongated members also being provided with other heads bearing against the lower surfaces of the retainer plates.

4. In a coupler support, a support member having spaced forward and rear transverse walls and having a spring seat therebetween, a carrier iron resiliently supported by said seat and having forward and rear surfaces above respective walls, said carrier iron having spaced side walls with oppositely facing recesses, respectively, between said surfaces, said support member having upstanding side walls approximately perpendicular to said forward and rear walls, said last mentioned side walls having slots therethrough aligned with respective recesses, flanges on the outer surfaces of respective last mentioned side walls, plates extending through respective slots and having their outer ends detachably connected to the flanges, the inner ends of the plates being received within the recesses and being disposed above and engageable with upwardly facing surfaces of the carrier iron to limit upward movement thereof, said recesses being of greater depth than that of said plates to accommodate vertical movement of the carrier iron.

5. In a coupler support, a striking casting having side walls partly defining an opening for the reception of a coupler shank, a spring pocket in said casting, a carrier iron, precompressed resilient means in said pocket supporting said carrier iron, oppositely facing recesses in opposite sides of the iron, respectively, said recesses opening toward respective side walls, slots through respective side walls registered with said recesses, and a pair of elongated spaced plates aligned end to end thereof and having their adjacent ends projecting through the respective slots and into the respective recesses; said ends being engageable with upwardly facing surfaces of the carrier iron, and means disposed entirely externally of said opening for detachably connecting the plates

at the ends thereof remote from each other to the respective side walls.

6. In a coupler support, a striking casting having top and bottom and spaced side walls defining a coupler shank opening, forward and rear transverse webs upstanding from said bottom wall and angularly related to the side walls to define a spring pocket therebetween, spring means seated on said bottom wall in said pocket between said webs, a carrier having downwardly facing forward and rear surfaces overlying respective webs, said carrier having depending fore and aft transverse walls between said webs, said spring means extending between said fore and aft walls and bearing against said carrier between said surfaces to support said carrier, said carrier having depending side walls with oppositely facing recesses, respectively, between said surfaces of said carrier, slots in said first mentioned side walls partly defined by outturned flanges thereof, readily removable plates seated along the underside of said flanges, said plates having their adjacent ends projecting into respective recesses, the inner ends of said plates being disposed above and being engageable with upwardly facing surfaces of the carrier to limit upward movement thereof under the action of said spring means, and elongated retainer members extending through complementary openings of respective plates and through complementary openings of the respective flanges.

7. In a coupler support, a striking casting having top and bottom walls and spaced side walls defining an opening for reception of an associated coupler shank, slots through the side walls, outturned flanges on the side walls above the slots, a pair of spaced elongated plates arranged in alignment endwise of each other, the outer ends of the plates being removably attached to respective flanges at points externally of said opening, a carrier, resilient means precompressed between the bottom wall and a downwardly facing surface of the carrier, the inner ends of said plates being engaged with upwardly facing surfaces of said carrier to limit upward movement thereof and to maintain said resilient means under precompression.

8. In a coupler support, a support structure having an opening for the reception of an associated coupler shank, a carrier, precompressed resilient means supporting the carrier from the bottom of said opening, slots through the sides of said structure communicating with said opening and partly defined by outturned flanges on the sides of said structure, a pair of spaced elongated plates arranged in alignment endwise of each other, the outer ends of the plates being removably attached to respective flanges at points externally of said opening, said plates extending through respective slots and having their inner ends engaged with upwardly facing surfaces of the carrier to limit upward movement thereof and to maintain said resilient means under precompression.

9. In a coupler support, a support structure having an opening for reception of an associated coupler shank, a carrier resiliently supported by said structure at the bottom of said opening, slots through the sides of said structure communicating with said opening, outturned flanges integrally formed on opposite sides of said structure and projecting therefrom, said flanges having downwardly facing surfaces partly substantially coplanar with the upper edges of said slots, elongated plates snugly seated against

5 said surfaces and edges, said plates projecting through respective slots, the inner ends of the plates being engageable with upwardly facing surfaces of the carrier to limit upward movement thereof, and elongated members projecting through the flanges and plates, said members having heads bearing against the upper surfaces of the flanges and against the lower surfaces of the plates to maintain them against the downwardly facing surfaces, each elongated member being spaced a greater distance from the opening than the distance between the adjacent upwardly facing surface and the related slot.

10. In a coupler support, a structure adapted to support an associated coupler shank, a carrier iron resiliently supported by said structure, aligned slots in opposite sides of said structure, outturned flanges projecting from remote sides of the structure and partly defining the upper edges of said slots, elongated plates extending through said slots and having their inner ends engageable with upwardly facing surfaces of the carrier to limit upward movement thereof, and detachable means connecting the plates to the flanges, each of said detachable means being spaced from the inner end of the related slot a distance greater than that between the adjacent upwardly facing surface and the inner end of said slot.

11. A coupler support comprising a support structure, a carrier resiliently supported thereby, aligned slots through opposite sides of said structure, outturned flanges projecting from opposite sides of said structure above said slots, elongated plates arranged in alignment endwise of each other and extending through respective slots, the inner ends of the plates being engageable with upwardly facing surfaces of the carrier to limit upward movement thereof, and spaced detachable means connecting respective plates to the related flanges, the distance between each detachable means and the inner end of the related slot being substantially greater than that between the adjacent upwardly facing surface and said inner end of said slot.

12. In a coupler support, a support structure, a carrier resiliently supported thereby, slots through opposite sides of said structure, plates separable with respect to said structure and extending through respective slots for engagement with upwardly facing surfaces of the carrier to limit upward movement thereof, readily detachable means externally of the slots for securing the plates to said structure, said detachable means being characterized by substantially vertical elongated members extending through aligned openings in the support structure and plates, and heads on said elongated members bearing against oppositely facing surfaces of said structure and flanges, each elongated member being spaced from the inner end of the slot a distance greater than that between the adjacent upwardly facing surface and the inner end of said slot.
